US00D786544S

(12) **United States Design Patent** (10) Patent No.: **US D786,544 S**
Marvin et al. (45) Date of Patent: **** May 16, 2017**

(54) **SHOE MIDSOLE**

(71) Applicant: **Reebok International Limited**, London (GB)

(72) Inventors: **William Marvin**, Canton, MA (US); **Matthew Montross**, Middleboro, MA (US)

(73) Assignee: **Reebok International Limited**, London (GB)

(**) Term: **15 Years**

(21) Appl. No.: **29/549,289**

(22) Filed: **Dec. 21, 2015**

Related U.S. Application Data

(62) Division of application No. 29/470,409, filed on Oct. 21, 2013, now Pat. No. Des. 746,032, which is a division of application No. 29/443,382, filed on Jan. 16, 2013, now Pat. No. Des. 693,552, which is a division of application No. 29/378,310, filed on Nov. 2, 2010, now Pat. No. Des. 675,002.

(57) **CLAIM**

The ornamental design for a midsole, as shown and described.

DESCRIPTION

FIG. 1 is a side view of a shoe midsole showing the claimed design; and,

FIG. 2 is a bottom view thereof.

The broken lines in the figures show portions of the shoe midsole and environment that form no part of the claimed design.

1 Claim, 2 Drawing Sheets

UNITED STATES PATENT AND TRADEMARK OFFICE
CERTIFICATE OF CORRECTION

PATENT NO. : D786,544 S
APPLICATION NO. : 29/549289
DATED : May 16, 2017
INVENTOR(S) : Marvin et al.

Page 1 of 1

It is certified that error appears in the above-identified patent and that said Letters Patent is hereby corrected as shown below:

In the Claim, item (57):

“The ornamental design for a midsole, as shown and described.” should be --The ornamental design for a shoe midsole as shown and described.--

Signed and Sealed this
Ninth Day of January, 2018

Joseph Matal
Performing the Functions and Duties of the
Under Secretary of Commerce for Intellectual Property and
Director of the United States Patent and Trademark Office
